UNITED STATES PATENT OFFICE.

GEORGE J. SAYER, OF CHICAGO, ILLINOIS.

SAUSAGE-STUFFER.

1,091,537.

Specification of Letters Patent. Patented Mar. 31, 1914.

Application filed January 10, 1913. Serial No. 741,178.

To all whom it may concern:

Be it known that I, GEORGE J. SAYER, a citizen of the United States, residing at Chicago, in the county of Cook and State of Illinois, have invented a certain new and useful Improvement in Sausage-Stuffers, of which the following is a full, clear, concise, and exact description, reference being had to the accompanying drawings, forming a part of this specification.

My invention relates to sausage stuffers and kindred devices and has for its object the provision of an improved machine of this character.

15 My invention contemplates a machine of this character in which a movable piston may be used which is suitably actuated on one side by applied pressure, and which by its movement in answer to this pressure forces material out of the cylinder within which the piston operates.

25 My invention has several objects one of which primarily is to provide means whereby the cover of the cylinder, that is the cylinder head, may not be removed from the cylinder or tilted about its pivotal point on top of the cylinder until such time as the pressure has been released from the applied pressure side of the piston.

30 My invention further contemplates means whereby should the aforesaid cover be open and by some mischance the source of pressure connected to the applied pressure side of the piston, all danger of throwing the piston out of the cylinder is obviated. To accomplish this result I provide a releasing mechanism within the piston which operates when the cover is open and this pressure is applied to conduct this applied pressure outside of the cylinder without causing the piston to leave the cylinder.

35 My invention further contemplates improved packing means between the piston and cylinder, which packing means are responsive to the pressure upon the applied pressure side of the piston. In this way there is a tight joint provided between the piston and cylinder when the piston is under pressure and the pressure between the cylinder and piston is released when the pressure upon the applied pressure side of the piston is released, thus to permit the piston to fall readily by the action of gravity when the applied pressure is withdrawn.

40 I will explain one form of carrying out

my invention by referring to the accompanying drawings, in which:

Figure 1 is a side view of a machine constructed in accordance with my invention; Fig. 2 is a top view thereof; Fig. 3 is a side view at right angles to that of Fig. 1; Fig. 4 is a detail view of the toggle locking mechanism; Fig. 5 is a sectional view to illustrate the safety and packing devices associated with my improved piston, and Fig. 6 is a partial sectional view illustrating the cover on line a—a of Fig. 2.

Referring more specifically to Figs. 1, 2 and 3, I have a cylinder 1 into which a pipe 2 leads in the bottom thereof for the purpose of supplying pressure to the interior of the cylinder to thereby actuate a piston 3 which is shown more clearly in Fig. 5. A cover plate 4 is pivoted on the shaft 5 and carries at its top two outlets 6 and 7 which lead from the interior of the cylinder to the exterior thereof and are adapted for use for sausage stuffing or similar purposes as is well understood.

My invention concerns itself with suitable locking means for locking this cover 4 in place and preventing the destruction of the machine should pressure be applied when this cover plate is open and likewise to prevent destruction of the machine which would be likely to occur should an attempt be made to open this cover while the pressure is still acting against the applied pressure side of the piston. A three-way valve 8 controlled by a handle 9 controls the flow of pressure fluid from the pipe 10 through the pipe 2 to within the cylinder. This valve 8 may have any of the ordinary constructions in such a way that depending upon the position of the handle 9 pressure may be supplied to within the cylinder, or the supply may be cut off by closing the opening of the pipe 10 within the valve 8 and opening the pipe 2 to the atmosphere as may be desired to thereby release the pressure from within the cylinder and permit the piston to fall by gravity to be in position to take a fresh charge. A hinged cover plate has a locking device consisting of the two toggle elements 11 and 12, the element 11 consisting preferably of the two parts as shown which are pivoted at one extremity to the cover by means of the pin 13 and which are pivoted to the element 12 at the opposite extremity by means of the shaft 14. This shaft 14 is further controlled by a

handle 15 whose purposes will be presently explained. The element 12 is also in the nature of a handle and has at its top extremity two protruding arms 16, 16 which are adapted to enter notches 17, 17 provided in the two parts of the element 11. The arm 12 has also intermediate its ends a pair of arms 18, 18 which are adapted when the cover plate is closed and the handle 12 in the position shown in Fig. 1 to engage the under surfaces of lugs 19, 19 secured to the cylinder 1.

The elements 11 and 12 are in the nature of toggles and together with the handle 15 secure a complete closure of the cover plate 4 when in the position shown in Fig. 1. The valve handle 9 controls a connecting rod 20 which actuates a bracket 21 guided at its right hand extremity preferably by encircling the tube 2 and fastened at its left hand extremity to a slide 22, which is held in sliding position upon the cylinder 1 by means of the headed bolts 23, 23. This plate 22 carries a ring 24 which when the parts are in the position shown encircles the handle 12 and prevents its movement. The arm 21 likewise is directly across the path of the handle 15 to thereby prevent the movement of this handle 15, the parts being in the position shown. Now should the valve handle 9 however be moved to release the pressure from the cylinder, then this movement will lower the arm 21 and the plate 22 until the arm 15 is free to be rotated to unlock the devices 11 and 12, whereafter the arm 12 may be actuated, it now being clear of the ring 24 so that the actuation of this arm 12 may release the arms 18 from the lugs 19 to thereby permit the cover to be opened. A bracket 25 is used to hold the pipe 2 and its connecting elements in position. A pin 26 pivotally unites the handle 9 with the rod 20. From this it will be readily seen that the cover 4 cannot be opened as the arms 12 and 15 cannot be released until the valve handle 9 has shut off the pressure from the cylinder 1 and released the pressure therefrom. The position of the valve handle 9 in Fig. 1 allows the application of the pressure to the piston. When this valve handle 9 is rotated contra-clockwise, referring to Fig. 1 the pressure may be shut off by any suitable valve mechanism 8 as is readily apparent so that the arms 12 and 15 may be released. This release of course need not take place until the confined pressure within the cylinder has also been released, after the pressure from the source of supply has been cut off. Now should the cover plate 4 be open, the mechanism so far described would not prevent the re-application of the pressure from the source of supply to the applied pressure side of the piston within the cylinder. With the cover open, if the pressure is applied the piston of course would be blown out like a projectile. Referring however

more particularly to Fig. 5, I will describe the means which I set forth to prevent this violent projection of the piston from the cylinder in the event of the application of pressure thereto with the cover open. The piston herein is preferably made of two parts to facilitate constructional requirements, which parts consist of the upper portion 27 and the lower 28. A hollow portion 29 may be provided which communicates by means of ducts 30 to the applied pressure side of the piston within the cylinder. Bolts 31 may be provided having adjusting devices in the form of distance pieces 32 and nuts 33 for the purpose of adjusting the packing mechanism as will presently appear. Suitable ducts 34, 34 lead from the chamber 29 to the ports 35, 35, which ports are normally closed by the plates 36, 36 when the piston is entirely within the cylinder 1. In this illustration of Fig. 5 the piston is shown as being removed partially from the cylinder, that is, it is shown as having risen above the top of the cylinder on account of the application of pressure with the cover open. The plates 36 are automatically closed and held in position by the walls of the cylinder 1, but are blown outwardly when the piston in answer to this wrongfully applied pressure rises above the upper line of the cylinder, thereby permitting this pressure to escape through the duct 30, chamber 29, and duct 34 to the atmosphere, thus preventing the piston from being blown outwardly beyond the position shown in Fig. 5. After this pressure is again shut off and the pressure released from the under side of the piston, it will fall back by gravity and the plates 36 will again automatically close the ports 35.

A further improvement in this present construction, and which is necessitated by the requirement that the piston fall by gravity after release of the pressure is found in the method of packing employed and this consists of a flexible gasket or packing ring 37 which is held between two recessed portions 38, 38 of the elements 27 and 28. The amount of pressure which this element 37 exerts normally against the sides of the cylinder 1 may be regulated by the bolt mechanism 31 as will be readily apparent. This gasket 37 it will be seen is pressed outwardly against the cylinder when the machine is being used in direct response to the pressure applied against the piston. When the piston is so used the ports 35 are of course closed but the pressure from the under side of the piston and which actuates the piston likewise finds its way through the tube 30 into the space 29 where it may act against the gasket 37 to press it outwardly against the cylinder 1 with the same unit pressure which actuates the piston. A very secure means of packing is thus pro-

vided during the time the cylinder is in use, the pressure for which, however, is released when the piston actuating pressure is released, thus to permit the entire piston to fall by gravity at such time.

I have thus described one form which my invention may take, but it will of course be readily apparent to those skilled in the art that many modifications may be made from the structure herein disclosed without departing from the spirit of my invention.

Having however, thus described one specific form which it may take, what I claim as new and desire to secure by Letters Patent is:

1. A device of the character described having a cylinder, a piston movable therein, a cover plate for said cylinder, means to permit opening and closing said cover plate, means to control the supply of pressure to the said cylinder, and means controlled by said pressure controlling means to control the cover controlling means.

2. A device of the character described having a cylinder, a piston movable therein, a cover plate for said cylinder, toggle mechanism to permit opening and closing said cover plate, means to control the supply of pressure to the said cylinder, and means controlled by said pressure controlling means to control the cover controlling toggle mechanism.

3. A device of the character described having a cylinder, a piston movable therein, a cover plate for said cylinder, toggle mechanism to permit opening and closing said cover plate, a valve controlling handle to control the supply of pressure to the said cylinder, and means controlled by said pressure controlling handle to control the cover controlling toggle mechanism.

4. A device of the character described having a cylinder, a piston movable therein, a cover plate for said cylinder, toggle mechanism to permit opening and closing said cover plate, a valve controlling handle to control the supply of pressure to the said cylinder, a locking handle for said toggle mechanism, and means controlled by said pressure controlling handle to control the cover controlling means.

5. A device of the character described having a cylinder, a piston movable therein, a cover plate for said cylinder, toggle mechanism to permit opening and closing said cover plate, a valve controlling handle to control the supply of pressure to the said cylinder, a locking handle for said toggle mechanism, and means controlled by said pressure controlling handle to control the cover controlling means, said means including a sliding plate.

6. A device of the character described having a cylinder, a piston movable therein, a cover plate for said cylinder, toggle mechanism to permit opening and closing said cover plate, a valve controlling handle to control the supply of pressure to the said cylinder, a locking handle for said toggle mechanism, and means controlled by said pressure controlling handle to control the cover controlling means, said means including a sliding plate, a catch on said plate, a bar to hold said locking handle, and a connecting rod.

In witness whereof, I hereunto subscribe my name this twenty-first day of October, A. D., 1912.

GEO. J. SAYER.
